UNITED STATES PATENT OFFICE.

LEONARD D. SOUBIER, OF TOLEDO, OHIO, ASSIGNOR TO THE OWENS BOTTLE COMPANY, OF TOLEDO, OHIO, A CORPORATION OF OHIO.

GLASSWARE-ANNEALING LEER.

Application filed July 2, 1927. Serial No. 203,188.

The present invention relates to improvements in glassware annealing leers and particularly to that type comprising a tunnel through which ware is carried for heat treatment and tempering.

An object of the present invention is to provide a leer heating unit which may be so regulated and controlled that temperature conditions in the heating zone of the leer 10 may be maintained uniform throughout.

A further object is to provide a leer heating unit comprising a series of recuperator tubes grouped together and each equipped with an electric heating element. These 15 heating elements are so interconnected that any transverse set or sets may be entirely or in part rendered inoperative. Thus, the effectiveness of the heating unit is readily controllable so that the annealing medium 20 may be introduced into the heating zone at the desired degree of temperature and into the desired area. An advantage derived 25 from using a heating unit of the type herein disclosed, resides in the fact that hot centers and relatively cool side areas along the heating zone of the leer are eliminated. Accordingly, all ware passing through the heating zone is uniformly heated to the proper degree, and the creation of strains 30 and checks in the glassware is reduced to a minimum.

Other objects will be apparent hereinafter.

In the accompanying drawings:

Fig. 1 is a side elevation of the ware receiving end of a leer showing the control for the heating unit.

Fig. 2 is a sectional view through one of the recuperator tubes and its heating element, this section being taken substantially 40 on the line II—II of Fig. 3.

Fig. 3 is a sectional elevation taken substantially along the line III—III of Fig. 2.

Fig. 4 is a vertical central longitudinal 45 sectional view showing the improved heating unit applied to a leer.

Fig. 5 is a sectional view taken along the line V—V of Fig. 4.

Fig. 6 is a detail side elevation of one of the recuperator tubes and its heating element.

Fig. 7 is an inside plan view of one of the heating elements and the retainer.

Fig. 8 is a perspective view of one of the

switch members which control the supply of electric current to a transverse set of heating elements, the latter being diagrammatically illustrated.

Fig. 9 is a diagrammatic view of the electrical circuits.

Referring to the drawings, the leer comprises side walls 10 and cover 11, formed of suitable insulating material. A gate 12 is arranged at the ware receiving end, said gate being adjustable to vary the size of the opening 13 through which ware is placed upon an endless ware conveyor 14 extending lengthwise of the leer tunnel and running over sprockets 15 mounted on transverse shafts 16 (Fig. 4). The longitudinal reaches of the ware conveyor 14 are spaced apart vertically and between these reaches is arranged a heating unit and the conduits through which the heated air which forms the annealing medium returns to the heating unit after being exhausted from the leer 75 tunnel.

According to the present disclosure, the heating unit or recuperator comprises a hollow lower casting or base 17 which is open at its inner end providing communication 80 with a conduit 18 (Fig. 4) through which the annealing medium is returned to the recuperator. The upper wall 19 of the hollow base 17 is formed with a series of apertures 20 opening into transverse channels 85 or ways 21 in which slide valves 22 are seated. These slide valves are formed with openings (not shown) and are movable longitudinally in their respective channels to thereby control the exhaust of annealing 90 medium from the hollow base 17. This feature and the means for exhausting the annealing medium from the leer tunnel into the return pipe 18 are fully set forth in a copending application of Percy Q. Williams, 95 Serial No. 129,373, filed August 16, 1926, to which application reference may be had for details.

Recuperator tubes 23 (Figs. 4 and 6) are set upright on the base 17 in such position 100 that the longitudinal passageway 24 through each tube is vertically aligned with one of the openings 20 in the upper wall of the base 17. A top casting or retaining plate 25, also provided with a series of openings 105 26 aligned with the tube openings 24, is ar-

ranged upon the upper ends of the set of tubes 23. Thus, the tubes are held in proper assembly. The front end of the recuperator unit is left open and provided with deflector plates 27 by which a portion of the heat in the recuperator is applied directly to the ware conveyor pans just prior to arrival at the ware receiving station. Thus, the ware conveyor is preheated, eliminating the necessity for providing special apparatus for this purpose. The inner end of the recuperator or heating unit is preferably shut off from the remainder of the leer by a transverse wall 28 formed of suitable refractory and faced with an insulating material 29 which is held in place by a plate 30 (Fig. 4).

Each recuperator tube 23 is provided at its ends with rectangular heads 31 for properly spacing the tubes and holding them in position when assembled. The tubes are electrically heated so that they will suitably heat the air circulating through them and thereby provide an annealing medium of the desired temperature. For heating the tubes, a heating element 32 is provided for each tube, which element in the form of the invention illustrated, is carried by a retaining member 33 formed of asbestos or similar non-conducting material. The heating element is preferably of zigzag formation (Fig. 7) and arranged upon the inner face of the carrier or retainer 33. Each heating element and its carrier are applied to the corresponding recuperator tube (see Figs. 2, 3 and 6), the carrier forming a cylindrical jacket which entirely encloses the tubular body between the heads 31 and is held in such position by retaining bands 35. The two ends 34 (Fig. 7) of the heating element are brought to a position near the base of the tube and connected to terminal contacts 37 (Figs. 3 and 6) carried on the band 35. These contacts are vertically spaced, the upper contact being secured to an upstanding ear 36 on the retaining band 35, the contacts being insulated from each other.

The recuperator tubes are arranged in sets extending transversely of the leer, each set as shown in Fig. 5 comprising five tubes, there being eight sets of these tubes in the recuperator as shown. Obviously, the number of sets of tubes and the number of individual tubes in each set may be varied. In arranging a transverse set of recuperator tubes equipped with heating elements as above set forth, the contacts 37 are all positioned to face in the same direction, for a purpose hereinafter apparent.

Each transverse set of heating elements is regulated and controlled by a single controlling device, such as shown in Fig. 8, there being a separate controlling device for each set of heating elements. Referring particularly to Figs. 8 and 9, each controlling device comprises an electrical conductor 46

in the form of a rod or shaft extending transversely of the leer and mounted for rotative adjustment. On said rod are mounted collars 51 formed with lugs 50 adapted to be brought into electrical engagement with corresponding spring contacts 48 mounted on but suitably insulated from a transverse supporting rod 47. A spring contact finger 45 also mounted on the rod 47 bears continuously against the shaft 46 and is connected to the main line conductor "A". Each of the heating elements 32 has one end thereof electrically connected through a conductor 49 with a corresponding contact finger 48. The opposite ends of the heating elements are connected to a conductor 41 leading to the main "B". The mains "A" and "B" are fed from any suitable source of electrical current supply, herein indicated diagrammatically as a battery 44. A main control switch 43 in the main line can be opened to disconnect all of the heating elements from the source of current supply.

Each of the collars 51 is provided with one or more lugs 50, the number and arrangement of these lugs being such that by rotation of the shaft 46, the circuits for the heating elements 32 may be selectively established. For example, as shown in Fig. 8, the collars are so positioned that the lugs 50 on four of the collars (namely, all but the middle collar) are engaged with the four corresponding spring contacts 48, thereby supplying current to the corresponding pairs of heating elements at opposite sides of the center of the leer heating zone. The control rod 46 is mounted in bearings (not shown) in a housing 55 at one side of the leer and is manually rotatable by means of a knob 56 (Figs. 1 and 8). This knob carries a pointer 57 which works over a stationary dial plate 61 by which the operator may be guided in setting the controller. As shown, for example, in Fig. 8, the pointer 57 indicates that heating elements 1, 2, 4 and 5 are working while the central heating element is inactive. By a different adjustment, the outermost heating elements only may be retained in circuit, the three inner elements being cut out of circuit. By other adjustments, all the elements may be connected in the circuit or may all be disconnected. The collars 51 are preferably adjustable rotatively on the rod 46 and are also removable therefrom.

As indicated diagrammatically in Fig. 9, the several transverse sets of heating elements are connected in parallel to the mains "A" and "B" leading to the battery 44. Each transverse set of heating elements has associated therewith a housing or conduit 40 (Figs. 3 and 5) extending transversely across the leer, which housing encloses and protects within the recuperator, the conductors 49. Electrical connection between the con-

ductors 49 and the heating elements is provided by means of contacts 38 (Fig. 3) connected to the conductors 49 and positioned to engage with the lower terminal contacts 37. The upper contacts 37 bear against contacts 42 connected to the conductor 41, the latter as shown in Fig. 3 comprising a wall of the conduit 40.

The housing 55 for the current control devices communicates through a closed passageway 58 with a casing 59 which encloses the outer ends of the conduits 40 (Fig. 5).

In operating this type of leer, the main control switch 43 is closed so that the supply of current to the transverse sets of heating elements may be individually regulated by adjustment of knobs 56.

The annealing medium is circulated by any suitable propelling mechanism (not shown) and in its circulation passes upwardly through the recuperator tubes 23 wherein the medium is brought to the proper temperature for introduction into the heating zone. At times, conditions are such that application of additional heat to the annealing medium along the sides of the heating zone, and a decrease at the center would be of considerable advantage in annealing the ware.

With the above described heating unit, the elements at the opposite sides of the unit may be operated independently of the central unit to thereby balance the temperature transversely of the heating zone and cause uniform heating of ware passing through this zone. Because of the adjustability of the contact carrying collars 51 on the control rod 46, it is seen that various combinations may be obtained as required by the particular type of ware being annealed and in accordance with the individual requirements of any particular leer. The length and effectiveness of the heating zone may be accurately regulated by adjustment of the current control devices and may be further controlled by adjustment of the transverse slide valves 22 at the lower ends of the recuperator tubes 23. For example, the first five sets of tubes may be operating to heat the annealing medium passing therethrough into the heating zone, while the heating elements on the remaining tubes are inactive. It may be objectionable to allow any portion of the annealing medium to return to the heating zone without having been preheated in the recuperator. Under these conditions, the slide valves 22 are readily adjusted to close the lower ends of these remaining tubes, thereby forcing all of the annealing medium to pass through the tubes further forward in the unit. On the other hand, it may be desirable to operate alternate sets of the heating elements, utilizing the intermediate sets of tubes to merely convey portions of the annealing medium to the heating zone.

With this arrangement, there is introduced into the heating zone, separate streams of annealing medium of different temperatures. These separate streams co-mingle and if the current control devices are properly adjusted, this annealing medium resulting from mixing the several streams, is of the proper degree of temperature when it passes through the ware conveyor 14 into contact with the ware being annealed. Other various relative settings of the current control devices and adjustments of the slide valves 22 are obtainable to permit practically any desired temperature conditions in the heating zone and the ready application of additional heat to any area desired.

Various modifications may be resorted to within the spirit and scope of the appended claims.

What I claim is:

1. In a glassware annealing leer, a ware receiving tunnel, a heating unit at one end of the tunnel comprising a plurality of recuperator tubes, heating elements individual to the tubes, and means to vary the operation of the heating unit by rendering certain of the heating elements inactive.

2. In a glassware annealing leer, a ware receiving tunnel, a heating unit comprising a plurality of recuperator tubes through which the annealing medium passes for introduction into the tunnel, electric heating elements individual to the tubes, means to supply electric current to the elements, and means to shut off supply of current to certain of the elements to thereby vary the operation of the heating unit.

3. In a glassware annealing leer, a ware receiving tunnel, a heating unit comprising a plurality of transversely aligned sets of recuperator tubes, an electric heating element individual to each tube, means to supply electric current to the heating elements, and means to shut off the supply of current to any one or more of said sets of heating elements to thereby vary the operation of the heating unit.

4. In a glassware annealing leer, a ware receiving tunnel, a heating unit comprising a plurality of recuperator tubes arranged in transversely aligned sets, a heating element for each tube, means to supply electric current to the heating elements, current control devices individual to the transverse sets of tubes, and means whereby adjustment of the control devices varies the number of active heating elements.

5. In a glassware annealing leer, a ware receiving tunnel, a heating unit at one end of the tunnel comprising a plurality of recuperator tubes, electric heating elements individual to the tubes, means to supply electric current to the heating elements, controlling devices operable to shut off the supply of current to certain of the elements

- independently of other elements to thereby vary the effectiveness of the heating unit, and means to cause continuous circulation of an annealing medium through the recuperator tubes and leer tunnel.
6. In a glassware annealing leer, a ware receiving tunnel, a heating unit at one end of the tunnel comprising a plurality of recuperator tubes, electric heating elements individual to the tubes, means to supply electric current to the heating elements, controlling devices operable to shut off the supply of current to certain of the elements independently of other elements to thereby vary the effectiveness of the heating unit, means to cause continuous circulation of an annealing medium through the recuperator tubes and leer tunnel, and slide valves adjustable to eliminate certain of the tubes from the path of circulation of the annealing medium.
7. In a glassware annealing leer, a ware receiving tunnel, a heating unit at one end of the tunnel comprising a plurality of recuperator tubes, electric heating elements individual to the tubes, means to supply electric current to the heating elements, current flow control devices operable to shut off supply of current to certain of the elements independently of other elements to thereby vary the effectiveness of the heating unit, means to cause continuous circulation of an annealing medium through the recuperator tubes and leer tunnel, and a series of longitudinally spaced transversely adjustable valve slides operable to eliminate one or more groups of tubes from the path of circulation of the annealing medium.
8. A heating unit of the class described comprising sets of transversely spaced tubes, electric heating elements individual to the tubes, means to supply electric current to the heating elements, and current flow regulators individual to each transverse set of tubes.
9. A heating unit of the class described comprising sets of transversely spaced tubes, electric heating elements individual to the tubes, means to supply electric current to the heating elements, current flow regulators individual to each transverse set of tubes, and means whereby adjustment of each regulator functions to vary the number of effective heating elements in each transverse set.
10. A heating unit of the class described comprising sets of transversely spaced tubes, electric heating elements individual to the tubes, means to supply electric current to the heating elements, current flow regulators individual to each transverse set of tubes, and valve slides adjustable to partially or completely close any one or more sets of tubes.
11. A heating unit of the class described comprising sets of transversely spaced tubes, electric heating elements individual to the tubes, means to supply electric current to the heating elements, current flow regulators individual to each transverse set of tubes, and valve slides adjustable to partially or completely close any one or more sets of tubes.
- tubes, means to supply electric current to the heating elements, current flow regulators individual to each transverse set of tubes, means whereby adjustment of each regulator functions to vary the number of effective heating elements in each transverse set, and valve slides adjustable to partially or completely close any one or more sets of tubes.
12. A heating unit of the class described comprising horizontally spaced sets of transversely aligned tubes, a top frame member arranged upon the tubes and formed with openings aligned with passageways through the tubes, a hollow base member supporting the tubes and having openings aligned with the passageways through the tubes, slide valves adjustable to shut off communication between said hollow base and said passageways, and electric heating elements individual to the tubes.
13. A heating unit of the class described comprising horizontally spaced sets of transversely aligned tubes, a top frame member arranged upon the tubes and formed with openings aligned with passageways through the tubes, a hollow base member supporting the tubes having openings aligned with the passageways through the tubes, slide valves adjustable to shut off communication between said hollow base and the tubes, electric heating elements individual to the tubes, means to supply electric current to the heating elements, and current flow control regulators individual to each transverse set of elements.
14. A heating unit of the class described comprising horizontally spaced sets of transversely aligned tubes, a top frame member arranged upon the tubes and formed with openings aligned with passageways through the tubes, a hollow base member supporting the tubes having openings aligned with the passageways through the tubes, slide valves adjustable to shut off communication between said hollow base and said tubes, electric heating elements individual to the tubes, means to supply electric current to the heating elements, current flow control regulators individual to each transverse set of elements, and means whereby each current flow control regulator may be adjusted to vary the number of active heating elements in the corresponding transverse set.
15. In an annealing leer, the combination of a heating chamber, a set of electrical resistances in said chamber arranged at intervals transversely thereof, and a controlling device manually operable to selectively connect said resistances in circuit with a source of current supply.
16. In an annealing leer, the combination of a heating chamber, a set of electrical resistances in said chamber arranged at intervals transversely thereof, and a controlling device manually operable to selectively connect said resistances in circuit with a source of current supply.

device manually operable to selectively connect said resistances in circuit with a source of current supply, said controlling device comprising contacts so arranged that in one position of adjustment only the outer said resistances are connected in circuit, in another adjustment all of said resistances are connected in circuit, and in another adjustment all of said resistances are rendered in-
active.

17. In an annealing leer, the combination of a heating chamber, a plurality of sets of electrical resistances within said chamber, each set comprising a series of individual resistances spaced at intervals transversely of the chamber, said sets being arranged one in advance of another in a direction lengthwise of the leer, manually operable controlling devices individual to said sets of resistances, and conductors leading from the resistances to a source of current supply, each said controlling device being operable to selectively

connect the resistances of the set in the circuit.

18. In an annealing leer, the combination of a heating chamber, a multiplicity of electrical resistances in said chamber, said resistances being arranged to form rows extending transversely of the leer and also in rows extending lengthwise of the leer, and controlling devices for selectively connecting the resistances in circuit with a source of current supply, said controlling devices being operable to selectively connect in circuit the individual resistances in the rows extending in one of said directions and for selectively connecting in the circuit the individual rows of resistances extending in the other said direction.

Signed at Toledo, in the county of Lucas and State of Ohio, this 30th day of June, 1927.

LEONARD D. SOUBIER.
